Edwin Wright

UNITED STATES PATENT OFFICE.

FREDERICK BOOTH, OF MICHIGAN CITY, INDIANA.

TOOL HOLDER.

Application filed February 24, 1923. Serial No. 620,949.

To all whom it may concern:

Be it known that I, FREDERICK BOOTH, a citizen of the United States, residing in Michigan City, in the county of LaPorte and State of Indiana, have invented certain new and useful Improvements in Tool Holders, of which the following is a specification.

The invention relates to tool holders of the 10 class in which a handle is provided with means for holding a screw driver, drill, or other tool in such manner that the holder may be rotated by pressing upon the handle to reciprocate it. It particularly relates to 15 tools of the kind shown in my prior Patents No. 1,183,426, of May 16, 1916, and 1,330,053, of Feb. 10, 1920.

An object of the invention is to provide improved means for rotating the tool in 20 either direction as desired, or for holding it against rotation when in any position.

Another object is to provide a means for holding the parts rigid when in fully extended position, or when in fully retracted 25 position.

Another object is to provide means for preventing inadvertent change of the various adjustments.

Another object is to provide improved 30 means for preventing rotation of the tool upon return movement of the parts.

Other objects will be apparent from the following detailed description and the appended claims.

35 In the drawings:

Figure 1 is a perspective view of the tool.

Figure 2 is a longitudinal section thereof.

Figure 3 is a separated view of details of the clutch mechanism.

40 Figure 4 is a longitudinal section of a portion of the tool, on a larger scale than Figure 2.

Figures 5, 6 and 7, are cross sections on the lines 5—5, 6—6, and 7—7, respectively.

45 Figures 8 and 9 show modifications of the end bearing members for the spindle. Each of these figures shows two modifications, one above and the other below the dot and dash line.

50 Figure 10 is a modification of one end of the casing.

A handle 1 has secured therein a metallic tubular casing 2 within which is the tool actuating mechanism. In the outer end of 55 this casing is fitted a bearing plate 3 and an end plate or cap 4 is fastened to the cas-

ing 2 by screws 5 which pass through the cap and casing and into the bearing plate 3. Between the cap and bearing plate is placed a felt or similar packing 6 which prevents 60 access of dust and egress of lubricant.

The outer reduced end of the spindle 7 is provided with a reduced portion upon which is mounted the body 8 of a chuck device. The tool 9 has a milled slot 10 to engage a 65 corresponding tongue 11 on the end of the spindle. The tool is also provided with a shoulder 12 against which bears a nut 13 which is screwed into an internally threaded portion of the body 8. The customary loose 70 sleeve 14 encloses the body as shown.

The reduced inner end 15 of the spindle 7 is carried by a bearing which slides within the tube 2 and is particularly shown in Figures 4 and 5. This comprises inner and 75 outer raceways 16 and 18 between which are rollers 17. Inclosing the whole is a shell 19 which acts as a retainer. An end piece 20 is fastened in place by a screw or similar fastening member near the end 21 of the 80 spindle. Between the down turned portion of the shell 19 and the shoulder formed by the reduced portion of the spindle 7 are mounted hardened thrust washers 22 having between them a ball retainer 23 carrying 85 balls 24. This mounting permits the spindle to turn freely, since the side thrust is taken by the roller bearings 17 and the end thrust by the balls 24. The shell 19 fits smoothly within the tube 2 and slides freely along the 90 same.

Fastened to the inside of the tubular casing 2 is a driving rack 25 of the general type shown in my prior patents, and with this rack mesh two gears 26 and 27, the gear 95 26 being a left hand gear and 27 a right hand gear. The gears are mounted freely on the spindle and held in position in the following manner. The gear 27 bears at one end against one of the hardened washers 100 22 and at the other end against a shoulder on the spindle. The other end of the gear 26 abuts against a bearing 28 which fits tightly on the spindle.

A shifting member 31 shown in perspective in Figure 3 is slidably mounted on the spacing sleeve 30 between the two gears. A key 32 fits in a longitudinal slot 33 in the spindle and has a projection 34 passing through a slot 35 in the sleeve 30 and fitting 110 within an annular groove 36 on the inside of the shifting member 31. The key must

rotate with the spindle, while the shifting member 31 only has a longitudinal movement on the sleeve 30, and the groove 36 is necessary to permit rotary movement of the key independent of the member 31 but to insure that the key will move longitudinally with said member. The member 31 is provided with a cut out 37 which fits over the driving rack 25, and with a cut out 39 for a purpose hereinafter mentioned. The member 31 has a projecting sharp edge 40.

The key 32 is spring pressed outwardly by a spring 41 in the slot 33 and is adapted to couple the spindle to either or both of the gears 26 and 27. These gears are provided with internal ratchet teeth 42 having straight faces on one side and inclined faces on the other. When the parts are in the position shown in Figure 4, the key is engaged with the teeth of the gear 27, and a relative endwise movement of handle and casing will cause the key 32 to engage the straight sides of the teeth 42 so that the turning of the gear 27 will through this key rotate the spindle in a right hand direction. If the key is shifted by movement of the member 31 to a position in which it engages only the gear 26, a left hand movement of the tool will be obtained. If the key is moved to an intermediate position wherein it engages both gears 26 and 27, the parts will be rigidly held and the tool may be used in the ordinary manner. Upon return movement of the parts, no matter which gear the key 32 engages, the key will contact with the slanting sides of the ratchet teeth 42 and be cammed out of their path against the tension of the spring 41, thus permitting said return movement to take place without any turning of the tool spindle. It may be here noted that the key may be set to engage both gears and make a rigid tool when the parts are fully extended, fully contracted, or in any intermediate position, thus enabling the length of the tool to be varied within considerable limits. The shifting member 31 and key 32 are moved to either of the three positions in the following manner. A rack bar 43 is carried by two headed screws or rivets 44 and 45 which pass through slots in the bar adjacent its ends. Springs 46 lie between the heads of the screws 44 and 45 and the rack bar 43 and normally press it outwardly. The rack bar 43 is provided with a pin or bent lug 48 adapted to fit in either of three holes A, B and C in the casing 2, and hold it in either of three positions, the parts of the other elements moving to positions designated by lines A, B and C upon Figure 2. The rack bar is also provided with a finger piece 49 which extends through a slot 47 in the casing 2, the slot and finger piece being protected against accidental displacement by a guard plate 50 provided with an open-

ing permitting engagement of the finger piece by the finger. The rack teeth of the bar 43, when pressed inwardly by the finger piece 49, will engage the sharp edge 40 of the member 31 and said member can thereby be moved to either of the three positions designated. Said rack bar 43 moves freely over the shifting member 31 at all times.

Through a circumferential slot in the casting 2 projects the finger piece 52 of a bar 53 of considerable extent as shown in Figure 2, which does not permit longitudinal movement but can have a circumferential movement within the limits of the slot. A guard plate 54 covers the finger piece and has an opening 55 sufficient to permit the finger to engage and move the bar 53 by means of the finger piece 52. When the parts are in one position the bar passes through the cut out 39 of the shifting member 31, a cut out 56 in the shell 19, and a cut out 60 in the member 28, and in no way affects the operation of the tool.

If the parts are fully extended and the bar is moved circumferentially to its second position, it will prevent return movement as it will engage the shell 19 as shown in Figure 4. Similarly, when the parts are in contracted position and the bar 53 is moved to the second position, it will then prevent relative endwise movement of the parts by contacting with the member 28. This bar therefore provides a second means for holding the parts in fully extended or in fully contracted position.

Figures 8 and 9 show certain modifications in the bearing for the end of the spindle, and to save space, the upper and lower halves of each figure show modified forms. In the upper half of Figure 8, the inner race way and rollers are the same as in the first form, but the outer raceway 18^a is a cylinder, and the shell 19^a is machined with a flange touching the reduced portion 15 of the spindle and against the washer 22.

In the lower half of Figure 8, the inner raceway is unchanged, but a slightly different form of roller 17^b is employed and the outer raceway 18^b has a flange engaging the end of the roller and the washer 22, while the shell 19^b is a simple cylinder.

In the upper half of Figure 9, the inner raceway is the same, but the outer raceway 18^c has an outwardly projecting flange at one end and an inwardly projecting flange at the other, the latter taking the place of one of the washers 22 and also providing means wherein the inner ends of the rollers 17^c are pivoted, their outer ends bearing in a washer 61.

In the lower half of Figure 9, the inner raceway 16 and washer 61 are as in the preceding modification, while the outer raceway 18^d and the shell 19^d resemble those of the

first form in Figure 4, except that the flange of the shell takes the place of one of the washers 22. Balls are used in the place of rollers.

5 Figure 10 shows a slight modification of the bearing at the other end of the spindle. The member 3^a takes the place of the bearing and cap of the first form and is held by screws 5 passing through the casing 2 and 10 into the same. Between the member 3^a and a washer 62 is placed absorbent packing 6^a.

The operation of the device is believed to be clear from the above description. The member 28 will also be provided with cut 15 outs for the driving rack 25 and the shifting rack 43 which have not been particularly identified on the drawings to avoid confusion.

It will be noted that the invention provides 20 a single clutch element which can be moved to engage with either or both gears, and thus cause the spindle to rotate in either direction, or hold it against rotation in any position. A separate means is also provided 25 to prevent the operation of the spindle when in either fully extended or fully contracted position. The guards for the finger pieces 49 and 52 are of importance in preventing accidental displacement of the mechanism 30 when set as desired. Experience demonstrates the tool to have over twice the efficiency of any other automatic tool of this type.

Obviously various detail changes can be 35 made without departing from the spirit of the invention, which is to be regarded as limited only by the scope of the appended claims.

I claim as my invention:

40 1. A tool holder comprising a casing, a spindle mounted for rotation and endwise movement in said casing, a rack bar extending longitudinally within said casing, gears mounted to rotate on said spindle and engaging 45 said rack, a clutch element on each of said gears, a clutch element carried by the spindle, and means for moving said spindle clutch element into engagement with either of said gear clutch elements.

50 2. A tool holder comprising a casing, a spindle mounted for rotation and endwise movement in said casing, a rack bar extending longitudinally within said casing, gears mounted to rotate on said spindle, and engaging 55 said rack, a clutch element on each of said gears, a clutch element carried by the spindle, and means for moving said spindle clutch element into engagement with either of said gear clutch elements or with both at one time.

60 3. A tool holder comprising a casing, a spindle mounted for rotation and endwise movement in said casing, a rack bar extending longitudinally within said casing, right 65 and left handed gears mounted to rotate on

said spindle and engaging said rack, a clutch element on each of said gears, a clutch element slidably carried by the spindle, and a 70 slidable but non-rotatable member for moving the last clutch element into engagement with either of the gear clutch elements.

4. A tool holder comprising a casing, a spindle mounted for rotation and endwise movement in said casing, gears 75 mounted to rotate on said spindle and engaging said rack, an internal clutch element on each of said gears, a clutch element slidably carried by said spindle intermediate said gears, and means for sliding the same 80 within either gear to engage its clutch element and thereby lock it to the spindle.

5. A tool holder comprising a casing, a spindle mounted for rotation and endwise movement in said casing, right and left hand 85 gears mounted on said spindle for rotation thereon, driving means for said gears meshing therewith, clutch elements on said gears, and a single clutch element for engaging the first named clutch elements to lock either 90 or both gears to the spindle.

6. A tool holder comprising a casing, a spindle mounted for rotation and endwise movement in said casing, right and left hand gears mounted on said spindle for rotation thereon, internal clutch teeth on each 95 of said gears, and a single clutch element slidably carried by the spindle and movable to engage the clutch teeth of either or both gears.

7. A tool holder comprising a casing, a spindle mounted for rotation and endwise movement in said casing, gears mounted on said spindle for rotation thereon, driving means for said gears meshing therewith, a 100 movable clutch element for locking either of said gears to the spindle, and means for preventing accidental displacement of said element when adjusted.

8. A tool holder comprising a casing, a spindle mounted for rotation and endwise movement in said casing, gears rotatably mounted on said spindle, driving means for said gears, means for clutching either gear to the spindle, manual means for operating 110 the same, and an overlying guard plate provided with a finger opening for preventing accidental displacement of said manual means.

9. A tool holder comprising a casing, a spindle mounted for rotation and endwise movement in said casing, means whereby the endwise movement of the spindle produces its rotation, means for locking the spindle against rotation and consequently against 115 endwise movement at extended, retracted, or any intermediate position, and a separate means for locking the spindle against endwise movement in fully extended or fully retracted position.

10. A tool holder comprising a casing, a spindle mounted for rotation and endwise movement in said casing, means whereby the endwise movement of the spindle produces 5 its rotation, two separate means for preventing endwise movement of the spindle, and means for preventing the accidental displacement of said means.

11. A tool holder comprising a casing, a 10 spindle mounted for rotation and endwise movement in said casing, driving means for said spindle, means for locking the driving means against rotation, and a separate means for locking the spindle against endwise 15 movement.

12. A tool holder comprising a casing, a spindle mounted for rotation and endwise movement in said casing, gears having internal clutch teeth mounted to rotate on the 20 spindle, a sleeve spacing apart said gears, a 25 slideable clutch member carried by said spindle, and slideable means on said sleeve adapted to move the clutch member into engagement with the clutch teeth of either gear.

13. A tool holder comprising a casing, a spindle mounted for rotation and endwise movement in said casing, gears having internal clutch teeth mounted to rotate on said spindle, a sleeve spacing apart said gears, a 30 key slidably mounted in a slot in the spindle, and means slideable on said sleeve and adapted to move said key into engagement with the clutch teeth of either gear.

14. A tool holder comprising a casing, a 35 spindle mounted for rotation and endwise movement in the casing, gears having internal clutch teeth mounted to rotate on said spindle, a key slideable in a slot in the spindle, a spring for pressing the key into engagement with the clutch teeth, and means for sliding the key into position to engage the clutch teeth of either gear.

In testimony whereof, I have hereunto subscribed my name.

FREDERICK BOOTH.
